UNITED STATES PATENT OFFICE.

CHARLES O'BRIEN, OF NEWTOWN, NEAR SYDNEY, NEW SOUTH WALES, AUSTRALIA.

CONCRETE BUILDING CONSTRUCTION.

Application filed September 11, 1922. Serial No. 537,508.

To all whom it may concern:

Be it known that I, CHARLES O'BRIEN, subject of the King of Great Britain and Ireland, residing at 106 Australia Street, 5 Newtown, near Sydney, New South Wales, Australia, have invented new and useful Improvements in and Relating to Concrete Building Construction, of which the following is a specification.

10 In carrying out my invention I provide outer form plates mounted on vertical standards, and collapsible sheet metal cores which are adapted to be aligned within the wall form plates and to be secured thereto by means of metal spacing pieces. The cores are of such a form that they overlap each other and have a minor portion of their length of reduced width so that when the mould is filled with concrete a vertical 15 strengthening rib is formed in the cavity faces of the wall shell. This form of core gives a wall section with maximum width of cavity between wall ties and minimum width of cavity at the vertical lines where wall ties 20 occur, thus permitting a much lighter construction of wall shell without reducing its strength.

To facilitate the supply of concrete to the mould the core boxes are surmounted with 30 sheet metal caps, and the wall form standards on each side of the wall are provided near their upper ends with links which serve to support a series of metal bow frames which span the cavity and carry a centrally 35 positioned continuous horizontal rail, which serves to support and guide a caster mounted on the end of an adjustable feeding chute.

In the drawings:—

40 Fig. 1 is a plan of a fragment of foundation wall plates showing the means by which the plates are connected together;

Fig. 2 is a side elevation of the same;

45 Fig. 3 is a plan of an external corner bracket;

Fig. 4 is a side elevation of a similar bracket;

50 Fig. 5 is a plan of the means for detachably securing together the ends of two adjacent boxes and positioning the wall ties;

Fig. 6 is a side elevation showing the means for collapsing the core boxes;

55 Fig. 7 is a side elevation of portion of an exterior wall mould showing wall form plates and vertical angle and T-iron standards;

Fig. 8 is a vertical section of a fragment of a wall mould supported by the foundation;

Fig. 9 is a plan of a wall mould showing 60 spacing members and reinforcements;

Fig. 10 is a side elevation of the means for securing wall form plates to the standards.

Fig. 11 is a plan of the same;

Fig. 11^a is a sectional detail of one of 65 the said vertical angle bars.

Fig. 12 is a sectional elevation of the upper portion of a wall mould, bow and rail;

Fig. 13 is a plan showing the means for 70 positioning the inner ends of one core box within an adjacent box.

Foundation plates 20, which are reinforced with angle iron bars 21, are detachably connected to each other in vertical 75 alignment by means of bolts 22 which pass through twisted locking fingers 23—24 secured to the plates. At the corners are positioned external and internal brackets 25—26 holed at 27. Through the holes 27 vertical 80 aligning rods 28 are passed. These rods are retained in position in the brackets by leaf springs 29 which are attached to the brackets and project slightly into the holes 27.

After the concrete foundation is completed, and the foundation plates removed vertical standards 30, 31, formed from T and angle iron bars to which wall form plates 32 are to be attached are positioned over the foundation. The lower ends 33, 34 90 of the standards, spaced by bolts 35, contact with the sides of the concrete foundation and the bolts 35 may rest on the foundation or pass therethrough. If desired, the standards 30 and 31 may be bolted to the 95 foundation plates before or after the foundation is completed.

The upper ends of the standards are spaced by means of bolts 36 and are provided with clips 37 to ensure the attachment 100 of horizontal angle iron bracing 38. Horizontal reinforcing wires or rods may be inserted through holes 39 in the vertical angle irons. The wall form plates 32 are reinforced with horizontal and vertical angle 105 iron pieces 40, 41 and are provided with twisted fingers 42, 43 which are constructed to ensure alignment of the plates and to permit longitudinal movement in one direction only. The upper and lower angle irons 110 40 of each form plate 32 are provided with integral or riveted end pieces 44 which are

bent at their ends 45 and make a wedge fit in tapering lugs 46 secured to the standards 30, 31.

Mounted in the upper ends of the standards 30, 31 are loose links 47 (Figs. 7 and 12) which are adapted to retain in position bows 48, bolts or bosses 49 on the bows preventing further downward movement of the bows. Carried by the bows 48 in a notch or bend 50 is a continuous rail 51 which lies centrally above the mould cavity and serves to support and guide the flanged caster 52 on the lower end of the feed chute 53.

Sheet metal core pieces 54 (Fig. 5) adapted to be mounted within and secured to the wall form plates 32 by metal spacing pieces, are reduced in width at the ends 55 so that they may be gripped by the free ends of shorter and narrower core pieces 56 which are bent to overlap each other at the inner ends and are slip riveted at 57, the stud of each rivet being adapted to travel in an inclined slot in the adjacent member 56'. The pairs of core pieces 56 are connected to each other by means of relatively narrow core boxes comprising sliding plates 58 which are provided with studs 59 to engage in inclined slots 60 in the pieces 56.

On drawing the plates 58 with the studs 59 upwards in the slots 60 the pairs of plates 56 are drawn towards each other and are thus freed from the reduced ends 55 of the cores 54. At the same time the studs 57 travel upwardly in the slots in the members 56', drawing the individual members of each pair towards each other, and permit the cores 54 and members 56 and 58 to be removed. Reverse movement of the plates 58, as shown in Figs. 5 and 6 locks the cores in position.

The wider free end of the core 64 is telescoped into or slipped within the open end of the core in the same wall cavity as shown in Fig. 13.

Placed across the core pieces 56 is a wall tie 61, kinked at 62. The tie rods are adapted to be wired through holes or notches 62^a, Fig. 8, in the outer and inner wall plates and secured temporarily thereto, thus preventing bulging of the form plates under pressure. Horizontal rods or wires 63 may also be inserted within the mould space to reinforce the wall.

To prevent the admission of concrete into the core boxes during the mould filling operation and to direct and distribute the flow into the mould, the core boxes 54 are protected by sheet metal caps 66 (Fig. 12).

What I claim as my invention and desire to secure by Letters Patent is:—

1. Means for moulding cavity wall reinforced or non-reinforced concrete structures in situ, comprising vertical angle and T-iron standards, inner and outer reinforced wall form plates, means for aligning said

wall plates with one another, means for detachably securing said wall form plates to said standards, transverse and horizontal spacing members secured to said standards, and alternately arranged relatively wide and narrow collapsible core boxes of sheet metal positioned between said form plates and the relatively narrow core boxes including means for detachably connecting the core boxes together. 75

2. Means for moulding cavity wall reinforced or non-reinforced concrete structures in situ, comprising vertical angle iron and T-iron standards, inner and outer reinforced wall form plates, means for aligning said wall plates with one another, means for detachably securing said wall form plates to said standards, transverse and horizontal spacing members secured to said standards, alternately arranged relatively wide and narrow collapsible core boxes positioned between said form plates, wall ties releasably carried on said core boxes and adapted to be arranged on the collapsing of the core boxes, and caps for said core boxes. 80

3. Means for moulding cavity wall reinforced or non-reinforced concrete structures in situ, comprising vertical angle iron and T-iron standards, inner and outer reinforced wall form plates mounted on said standards, means for aligning said plates, means for detachably locking said plates on said standards, transverse and horizontal spacing members secured to said standards, collapsible core boxes mounted between said plates, bows carried by said standards, a rail supported by said bows, a flanged caster adapted to travel on said rail, and an adjustable chute guided by said caster. 95

4. Means for moulding cavity wall reinforced or non-reinforced concrete structures in situ comprising vertical angle and T-iron standards, inner and outer reinforced wall form plates, means for aligning said wall plates with one another, means for detachably securing said wall form plates to said standards, transverse and horizontal spacing members secured to said standards, relatively wide collapsible core boxes positioned between said form plate and each having 110 restricted end portions and relatively narrow collapsible core boxes arranged between the side core boxes and releasably engaged with the restricted end portions thereof. 115

5. Means for forming cavity wall reinforced or non-reinforced concrete structures in situ, comprising vertical angle and T-iron standards, inner and outer reinforced wall form plates, means for aligning said wall plates with one another, means for detachably securing said wall form plates to said standards, transverse and horizontal spacing members secured to said standards, collapsible core boxes of sheet metal positioned between said wall form plates, restricted end 120

125

- portions on each core box, a pair of projecting plates at each restricted end, sliding plates connecting adjacent pairs of projecting plates, means for adjusting the position 5 of each member of a pair of projecting plates in relation to the other members of the same pair, and means for adjusting the positions of one pair of said plates relatively to the other pair of them.
- 10 6. Means for moulding cavity wall reinforced or non-reinforced concrete structures in situ, comprising vertical angle and T-iron standards, inner and outer reinforced wall form plates, means for aligning said wall plates with one another, means for detachably securing said wall form plates to said standards, transverse and horizontal spacing members secured to said standards, a collapsible core box of sheet metal positioned 15 between said form plates, an end portion of diminished width on said core member, and a free end adapted to be telescoped into the free end of an adjacent core member.
- 20 7. Means for moulding cavity wall reinforced or non-reinforced concrete structures in situ, comprising vertical angle and T-iron standards, inner and outer reinforced wall form plates, means for aligning said wall plates with one another, means for de- 25 tachably securing said wall form plates to said standards, transverse and horizontal spacing members secured to said standards, a pair of core boxes positioned between said form plates, diminished ends on said boxes, means 30 for detachably positioning the diminished end of one box adjacent to the diminished end of the other box, a wall tie supported by said positioning means, wall form plates positioned on each side of said boxes, and means for temporarily securing said wall tie to said wall plates.
- 35 8. Means for moulding cavity wall reinforced or non-reinforced concrete structure in situ, comprising vertical angle and T-iron standards, inner and outer reinforced wall form plates, means for aligning said wall plates with one another, means for detachably securing said wall form plates to said standards, transverse and horizontal spacing members secured to said standards, a pair of core boxes positioned between said form plates, diminished ends on said boxes, means 40 for detachably positioning the diminished end of one box adjacent to the diminished end of the other box, a wall tie supported by said positioning means, wall form plates positioned on each side of said boxes, and means for temporarily securing said wall tie to said wall plates.

In testimony whereof I affix my signature.

CHARLES O'BRIEN.
